US0D1043739S

(12) **United States Design Patent** (10) Patent No.: **US D1,043,739 S**
(45) Date of Patent: ** Sep. 24, 2024

(54) **DISPLAY SCREEN OR PORTION THEREOF WITH GRAPHICAL USER INTERFACE**

(71) Applicant: **Caleb Hernandez**, Denver, CO (US)

(72) Inventor: **Caleb Hernandez**, Denver, CO (US)

(73) Assignee: **Caleb Hernandez**, Denver, CO (US)

(**) Term: **15 Years**

(21) Appl. No.: **29/813,825**

(22) Filed: **Nov. 1, 2021**

(51) LOC (14) Cl. **14-04**

(52) U.S. Cl.

USPC **D14/492**

(58) **Field of Classification Search**

USPC D14/485-495

CPC G01F 19/00; A61M 5/32; G06F 19/3406;
A61B 5/02

(57) **CLAIM**

The ornamental design for a display screen or portion thereof with graphical user interface, as shown.

DESCRIPTION

The FIGURE is a front view of a display screen or portion thereof with graphical user interface.

The broken line illustrates a display screen or portion thereof that forms no part of the claimed design. The remaining broken lines in the drawing illustrate portions of the graphical user interface that form no part of the claimed design.

1 Claim, 1 Drawing Sheet
